Attorney

UNITED STATES PATENT OFFICE

JOHN ADAM GUTH, OF COVINGTON, KENTUCKY

ATTACHMENT FOR DUST COLLECTORS

Application filed May 12, 1928. Serial No. 277,281.

This invention relates to new and useful improvements in dust collectors that are used in saw mills, planing mills, and allied industries, and has more particular reference to a 5 particular attachment for generally conventional dust collectors of this character. In practically all saw mills, planing mills, and other factories, there is provided means for collecting the dust from the various machines, 10 these devices including a large structural unit arranged upon the roof of the building, and into which the dust collected from the various machines is projected, means being provided within the said units whereby to cause the 15 projection of the dust into a bin arranged upon the roof or at a lower level than said roof. These structural units arranged upon the building have a vent opening to permit the air to be discharged therefrom. It is a 20 known fact that very fine dust will be discharged with the exhaust air permeating the atmosphere for miles around, causing great annoyance to surrounding homes and buildings. My invention has for its object to provide 25 a device constructed for arrangement within the vent pipe of the structural unit of a generally conventional dust collector whereby the fine dust is positively collected and thence thrown downwardly through the 30 unit toward the dust bin, so that the air escaping from the vent of the unit will be free of all dust.

An important object of the invention is to 35 provide a device of this character that is extremely simple of construction and inexpensive of manufacture, and that may be installed in conventional dust collecting devices now in use without affecting the operation thereof or without requiring great expenditure for installation.

With the foregoing and other objects in view the nature of the invention will be better understood, the same comprises the novel form, combination and arrangement of parts 45 hereinafter more fully described, shown in the accompanying drawings and claimed.

In the drawings wherein like reference characters indicate corresponding parts throughout the several views:

Figure 1 is a fragmentary diagrammatic

section through a building equipped with a generally conventional dust collector, the dust separating unit thereof which is usually arranged upon the roof of the plant being equipped with my improved device.

Figure 1—A is a side elevation of my invention per se.

Figure 2 is an enlarged vertical fragmentary section through the fan unit of the device, and

Figure 3 is a horizontal transverse section taken through the fan unit at a point directly above the fan element.

Now having particular reference to the drawings, A in Figure 1 designates a fan housing of a generally conventional dust collector which is arranged within the building fragmentarily disclosed in Figure 1 and leading from which are dust collecting pipes *a* that extend to the various dust emitting machines within the plant. Leading from this fan housing A is a pipe *b* that extends upwardly within the plant and projects through an opening in the roof, while arranged upon the roof is the dust separating unit B of the said collector, which unit has communication with the housing A through the medium of said pipe *b*. This dust separating unit B includes among other elements a dust chamber or receiver *c* having communication at its lower end with a dust bin D, while leading from the top of the chamber *c* is a vent pipe E through which the air generated in the fan housing A is permitted to escape. My invention per se consists of a fan housing 5 of suitable area and design, the same having an intake pipe 6 at its lower end communicating with the upper interior of the chamber C at a point above the lower end of the vent pipe E, and a discharge pipe 7 at its upper end.

Rotatably mounted within this housing 5 is a fan 8, the blades of which are provided with felt or other absorbent material pads 9, the ends thereof projecting beyond the ends of the blades so as to engage at least the opposed end walls of the housing during the rotation of the fan. The shaft 10 upon which the fan unit is mounted extends through bearings within the opposed side walls of the housing 5, said shaft being op-

eratively associated at one end with a suitable electric motor 11, and supported and journaled at its opposite end within a suitable bearing 12. As disclosed in Figure 1, this device is arranged within the vent pipe E of the dust collector disclosed in Figure 1, said bearing 12 being suitably mounted within the vent pipe, while the said motor 11 is supported upon the top of the said chamber c of the separator B of the collector, the shaft 10 being arranged through an opening in said vent pipe, as disclosed. Arranged upon the upper end of the fan housing 5 is a fluid container 13 having a small discharge orifice 14 leading into the interior of the housing 5, said chamber having communication with a suitable capacity supply tank 15 which has communication with and is supported upon said chamber through the medium of a pipe 16 within which is located a regulating valve 17. Obviously the fluid dripping from the chamber 13 will fall upon the absorbent pads 9 so that when the dust comes into contact therewith it will be moistened and weighted, and insomuch as the exhaust pipe 7 of said housing 5 is located at a point beneath the inlet end of the vent pipe E of the separator unit B, said moistened dust will be reconveyed into the chamber c and eventually reach the collecting bin D.

It will thus be seen that I have provided a novel, simple, and extremely useful and efficient attachment for dust collectors, whereby to prevent the escape of fine dust through the vent pipes of said dust collectors, and even though I have herein shown and described the invention as consisting of certain detail structural elements it is nevertheless to be understood that some changes may be made therein without affecting the spirit and scope of the appended claims.

Having thus described the invention, what I claim as new and desire to secure by Letters Patent is:—

1. A moistening attachment for dust collectors, wherein the said collector includes a receiver, a vent pipe extending above the receiver and depending therein, said collector having an inlet; a rotary moisture containing body, a casing for said body, an inlet pipe communicating with said casing at one end and having its remote end disposed within the receiver and terminating at a point above the open end of the vent pipe, and an outlet 55 for the casing.

2. A moistening attachment for dust collectors, wherein the said collector includes a receiver, a vent extending above the receiver and depending therein, and an inlet, a rotary moisture containing body, a casing for said body, an inlet pipe communicating with said casing at one end and having its remote end disposed within the receiver and terminating at a point above the open end of the vent 65 pipe, and an outlet pipe for the casing, said

outlet pipe being disposed into the said receiver with its discharge end depending below the inner end of the vent pipe.

3. A moistening attachment for dust collectors, wherein the said collector includes a receiver, a vent extending above the receiver and depending therein, and an inlet, a rotary moisture containing body, a casing for said body, an inlet pipe communicating with said casing at one end and having its remote end disposed within the receiver and terminating at a point above the open end of the vent pipe, and an outlet for the casing, said moisture containing body comprising a shaft, a rotary member on the shaft provided with a plurality of radiating arms, and pads of moisture absorbing material secured to the said arms. 70 75 80

4. A moistening attachment for dust collectors, wherein the said collector includes a receiver, a vent extending above the receiver and depending therein, and an inlet; a rotary moisture containing body, a casing for said body, an inlet pipe communicating with said casing at one end and having its remote end disposed within the receiver, and terminating at a point above the open end of the vent pipe, and an outlet for the casing, said moisture containing body comprising a shaft, a rotary member on the shaft provided with a plurality of radiating arms, and pads of moisture absorbing material secured to the said arms, means for rotating the said shaft, and means for supplying liquid to the said pad. 85 90 95 100

5. A moistening attachment for dust collectors, wherein the said collector includes a receiver, a vent extending above the receiver and depending therein, and an inlet, a rotary moisture containing body, a casing for said body, an inlet pipe communicating with said casing at one end and having its remote end disposed within the receiver, and terminating at a point above the open end of the vent pipe, and an outlet for the casing, said moisture containing body comprising a shaft, a rotary member on the shaft provided with a plurality of radiating arms, and pads of moisture absorbing material secured to the said arms, means for rotating the said shaft, and means for supplying liquid to the said pad. 105 110 115 120 125

6. An attachment for dust collectors, wherein the collector includes a dust separating unit having an air vent pipe and a dust receiving bin; a fan housing arranged within the vent pipe and having an intake pipe, and an exhaust pipe, said exhaust pipe extending downwardly below the intake pipe, a rotary fan mounted within the housing whereby to draw the air and fine dust into 130

the housing and to deliver the fine dust into the separator unit at a point below the outlet of said separator unit vent pipe, and an absorbent material pad secured to the said fan 5 blade on the sides thereof forwardly of the direction of travel thereof.

7. An attachment for dust collectors wherein the collector includes a dust separating unit having an air vent pipe and a 10 dust receiving bin; a fan housing arranged within the vent pipe and having an intake pipe and an exhaust pipe, said exhaust pipe extending downwardly below the intake pipe, a rotary fan mounted within the housing 15 whereby to draw the air and fine dust into the housing and to deliver the fine dust into the separator unit at a point below the outlet of said separator unit vent pipe, and an absorbent material pad secured to the said 20 fan blade on the sides thereof forwardly of the direction of travel thereof, said pad adapted to be moistened whereby to settle the dust coming into contact therewith, and means for supplying fluid to said absorbent 25 pads.

In testimony whereof I affix my signature.

MR. JOHN ADAM GUTH.
